UNITED STATES PATENT OFFICE.

GEORGE R. SMITH, OF NORFOLK, VIRGINIA, ASSIGNOR OF ONE-HALF TO
JOSEPH E. BOWEN, OF NORFOLK, VIRGINIA.

COMBINED THROTTLE-VALVE AND STOP-VALVE.

No. 806,929.

Specification of Letters Patent.

Patented Dec. 12, 1905.

Application filed April 25, 1905. Serial No. 257,356.

To all whom it may concern:

Be it known that I, GEORGE R. SMITH, a citizen of the United States, residing at Norfolk, in the county of Norfolk and State of Virginia, have invented new and useful Improvements in a Combined Throttle-Valve and Stop-Valve, of which the following is a specification.

This invention relates to steam-boilers, and especially to those of the locomotive type. Its object is to provide an improved means for controlling the flow of steam from the boiler into the pipe which supplies the cylinders of the engine.

Although the device is applicable to various kinds of boilers, I shall, for the sake of simplicity, describe it in its application to a locomotive.

The throttle-valve of a locomotive is usually mounted on the upper end of an upright extension of the dry-pipe in a dome rising above the top of the boiler. The valve is operated by rods and levers which are located inside the dome and boiler and are connected through a stuffing-box with the throttle-valve lever in the cab. The result is that these parts frequently become corroded and rusty and clogged with mud and scale, so that in a large locomotive it requires a great deal of strength to operate them. Moreover, they are difficult to get at for repair, and it is of course necessary to blow off steam from the boiler before this can be done. The loss of time thus occasioned is serious, especially where there are many engines to keep in order. Furthermore, the modern locomotive has a number of attachments that require steam, and these are usually fed by connections tapped through the boiler-shell, making a large number of points where joints must be kept tight and where there is danger of accidentally knocking off a pipe and permitting an escape of steam. My invention aims to avoid all these troubles and many others also, as will appear from the following description.

It consists, in brief, of a combined stop and throttle valve mounted in a casing attached to the outside of the dome, where all parts are readily accessible and where connections can be easily made for the air-pump and other steam-operated attachments.

In the accompanying drawings, Figure 1 is a sectional elevation of a portion of a locomotive, showing my improvements. Fig. 2 is a rear elevation. Fig. 3 is a vertical section

of the valve, and Fig. 4 is a horizontal section thereof.

The steam-dome 1 rises from the boiler 2 near the cab 3, and in one side of it, preferably at the back, is cut a hole or holes to admit two necks 4 5, projecting from a casing 6, which is secured to the outside of the dome by a steam-tight joint. In this casing is mounted the throttle-valve and also, by preference, a stop-valve, both controllable from the cab by separate levers and rods. When both valves are used, the upper neck 4 admits steam to the stop-valve and the lower neck 5 conveys the steam from the throttle-valve to the dry-pipe 7, the two valves being located in separate chambers in the casing, which can be put in communication by operating said valves. By means of a short pipe 7' steam is taken from the upper part of the dome, where it is driest. The necks enable the pipes 7 7' to be attached by ground joints or with soft packing. In either case they can be made and tested from inside the dome.

The preferred form of construction is shown in Figs. 3 and 4, where it is seen that the casing has three chambers 8, 9, and 10, formed by suitable partitions 11, 12, and 13, which are stiffened by suitable ribs 14. The neck 4 communicates with the chamber 8 and the neck 5 with the chamber 10. In the partitions 11 and 13 are openings serving, respectively, as valve-seats for the stop-valve and the throttle-valve. These are preferably of the balanced type, as shown, having two valve-disks 15 15', connected by a spool 16 16', all mounted on a stem 17 17'. The stop-valve controls the flow of steam from the chamber 8 to the chamber 9, and the throttle-valve controls the flow of steam from the chamber 9 to the chamber 10. The stems 17 17' pass out through stuffing-boxes 18 on bonnets 19, secured over openings in one end of the casing, and are provided with suitable heads 20 for the attachment of the operating mechanism. This preferably comprises rock-shafts journaled concentrically in a bracket on the casing and provided with rock-arms 21, carrying wrist-pins engaging with slots in said heads, and rock-arms 22, connected by rods 23 and bell-crank levers 24 with actuating-levers 25 in the cab, pivoted side by side, so as to be readily handled. A screw-plug 26 is inserted in the casing in line with the stem of the throttle-valve for a purpose hereinafter

set forth. One or more suitable apertures 27 are formed in the casing for the attachment of the air-pump, injector, &c. These apertures open into the intermediate chamber 9.

5 The operation of my invention is as follows: When steam is raised, it fills the chamber 8 through the pipe 7', so that when the stop-valve is opened wide dry steam is admitted to the intermediate chamber 9. This 10 steam is at once available for the air-pump and other steam attachments. When the engine is to be started, the throttle-valve is opened gradually, and the flow of steam through the dry-pipe is regulated thereby in the usual 15 manner. At the end of the run, when the locomotive is taken to the roundhouse, the stop-valve can be closed, cutting off live steam from the chambers 9 and 10 and also from the dry-pipe, so that without blowing off 20 steam from the boiler it is possible to take off the bonnet 19 and inspect the throttle-valve and remove it for regrinding or otherwise repairing it, if necessary. Since the operating mechanism is all outside of the boiler, 25 it is not subject to corrosion or clogging, so that the engine can be handled with far less labor on the part of the runner. After the engine has been set up the throttle-valve and dry-pipe can be tested by hydraulic pressure 30 independently of the boiler test, so that a man can examine the dry-pipe from one end to the other and be sure that it is all right.

In case the operating mechanism of the throttle-valve should get out of order the 35 valve can be forced off its seat by means of the screw-plug 26 and held open thereby. The stop-valve can then be used as a throttle-valve by means of its operating mechanism, thus saving delays in traffic.

40 The valves can be arranged in any position that is most desirable, though I prefer to place them with their stems horizontal, as shown in the drawings.

Having thus described my invention, what 45 I claim is—

1. The combination with a boiler having a steam-dome, of a casing secured to the outside of said dome and communicating therewith, a pipe leading from said casing, a hand-operated 50 stop-valve controlling the admission of steam to said casing, and a valve controlling the admission of steam from the casing to the pipe.

2. The combination with a boiler having a steam-dome, of a casing secured to the outside 55 of said dome and containing three chambers, one of which communicates with said dome, a valve controlling the passage of steam from said chamber to the next, and a valve controlling the flow of steam from the second to 60 the third chamber.

3. The combination with a boiler having a steam-dome, of a casing secured to the outside 65 of said dome and containing three chambers, one of which communicates with said dome, a valve controlling the passage of steam from

said chamber to the next, and a valve controlling the flow of steam from the second to the third chamber, said valves being provided with operating mechanism passing through the walls of said casing.

4 The combination with a boiler having a steam-dome, of a casing secured to the outside of said dome and containing three chambers, one of which communicates with said dome, a valve controlling the flow of steam from said 70 chamber to the intermediate chamber, a valve controlling the flow of steam from the intermediate chamber to the third, a dry-pipe leading from said third chamber, and separate means for operating said valves from outside 75 the casing.

5. The combination with a locomotive-boiler provided with a steam-dome and a dry-pipe, of a throttle-valve and a stop-valve both located outside of said dome, and both controlling 80 the passage of steam from said dome to the dry-pipe.

6. In a locomotive, the combination with the steam-dome, of a casing secured to the outside thereof, a stop-valve and a throttle-valve 90 mounted in said casing, and separate operating mechanism leading back to the cab outside of the boiler.

7. In a locomotive, the combination with the steam-dome and dry-pipe, of a stop-valve and 95 a throttle-valve both controlling the flow of steam to the dry-pipe and separate means for operating said valves by hand.

8. In a locomotive, the combination with the steam-dome and the dry-pipe, of a stop-valve 100 and a throttle-valve both controlling the flow of steam to the dry-pipe, and means for holding the throttle-valve permanently open in case of accident to its operating mechanism.

9. In a locomotive, the combination with the 105 steam-dome, of a casing secured to the outside thereof, a stop-valve and a throttle-valve both located in said casing, operating mechanism located outside the boiler, and means for forcing open the throttle-valve in case of accident 110 to its operating mechanism.

10. In a locomotive, the combination with the steam-dome, of a casing secured to the outside thereof, a stop-valve and a throttle-valve both located in said casing, operating 115 mechanism for each valve located outside the boiler, and a screw-plug passing through the wall of the casing in line with the stem of the throttle-valve.

11. In a locomotive, the combination with the steam-dome, of a casing for the throttle-valve secured to the outside of said dome and having two necks projecting into said dome.

In testimony whereof I have signed my name to this specification in the presence of two sub- 125 scribing witnesses.

G. R. SMITH.
